METAL WOOL BODY AND METHOD OF MAKING SAME

George W. Brooks, La Grange, Ill., assignor to
The S. O. S. Company, Chicago, Ill., a corpora-
tion of Delaware

Application May 11, 1935, Serial No. 20,942

3 Claims. (Cl. 140—71)

The present invention relates to the art of making or producing metal wool bodies, more particularly metal wool pads.

In the producing of metal wool pads such as are used for cleansing and scouring purposes, there has existed a disadvantage in that the fibres going to make up the pad are easily separated or torn apart when a pull is effected or imposed upon the pad. This is particularly so when the fibres are short and not so interlaced or interwoven as to hold together.

To avoid such a disadvantage, it has been proposed to use fibres of greater length and to wind a sheet or ribbon or web of such fibres into a cylindrical form and then flatten the cylinder to produce a sort of square or rectangular pad. Such a pad easily tears apart when a pull is effected in the axial direction of the cylinder or the pad made from it. The disposition of the fibres is only in one direction.

The present invention comprehends the winding into a body of any desired shape of a plurality of long metal fibres or filaments of indefinite length continuously in web loops in different directions so that the disposition of all or part of the fibres will be in more than one direction. Any pull on the mass of that body in more than one direction will be resisted by the fibres disposed in such direction and hence it is impossible normally to tear the fibres apart. Even when the body is flattened into the form of a pad the disposition or arrangement of the fibres to extend in more than one direction across the pad, irrespective of the shape of the pad, offers resistance in more than one direction of pull that might or would ordinarily tear the fibres or filaments apart in the older forms of pads.

The invention also comprehends a novel metal wool body or pad of the kind described above.

Other objects, advantages, capabilities, features, process steps and the like are comprehended by the invention as will later appear and as are inherently possessed thereby.

Referring to the drawing:

Fig. 1 is a plan view of a fragment of a plurality of metal fibres of any desired length, arranged in sheet or ribbon form;

Fig. 2 is a perspective view showing a stage of winding the ribbon or web in different directions continuously in loops;

Fig. 3 is a view of a completed wound body;

Fig. 4 is a top plan view of a pad made from the body shown in Fig. 3; and,

Fig. 5 is a side view of such a pad.

Referring more in detail to the drawing and

for the purpose of illustrating the invention, a plurality of long metal fibres or filaments 1 of indefinite length as desired are arranged in a more or less parallel relation so as to form a sheet or ribbon or web 2. An object of this invention is to so wind the ribbon or web that there will be a crossing and/or recrossing of the fibres or filaments by the parts being wound on the parts previously wound, whereby the fibres or filaments in the wound mass or body will be arranged in more than one direction of the body. As for example, the winding may be started by turning a corner portion 3 to dispose the fibres at an angle or transversely to the fibre portion 4 of the ribbon, and then turning another corner portion 5 likewise across or at an angle to the fibre portion 4. Then the end portion 6 may then be turned to dispose the fibres across the previously turned portions 3 and 5, and so forth until a suitable core is formed. It is immaterial just what shape this core may take whether round or otherwise. Then the ribbon or web is wound on the core so as to dispose a portion such as portion 7 (Fig. 2) in one direction of winding. As the winding progresses the ribbon or web is caused to extend across or at an angle to the previously wound portion, such as portion 8, shown in Fig. 2, and thence further winding brings such a portion 9 across the portion 8, etc. While the showing in the drawing for purposes of illustration is that in the form of a ball it is to be understood that any shape of the body may be produced.

To produce the pad as shown in Figs. 4 and 5 it is preferable to compress or flatten the body shown in Fig. 3. This does not disturb the relation of the fibres. As will be seen in Figs. 4 and 5 the fibres or filaments run across the pad and also around the edge portions of the pad in more than one direction, the fibres of a portion crossing the fibres of another portion so that they are interlaced or interwoven and so disposed that any pull imposed on the pad in more than one direction will be opposed or resisted by the fibres disposed in that direction thus preventing the tearing apart of the fibres or filaments, especially those disposed transversely to the fibres or filaments subjected to the pull.

Such a pad is durable, has a long life, and will be more efficient in its use, especially when used with soap whether impregnated or otherwise as a scouring pad.

While I have herein disclosed an illustrative embodiment of the invention and a mode of producing it, it is to be understood that this is mere-

ly illustrative and not by way of limitation and other forms and other process steps may be used without departing from the spirit of the invention.

5 Having thus disclosed the invention,
I claim:

1. A metal wool mass composed of metal fibre web loops extending in more than one direction in the mass and being so arranged and disposed 10 as to resist separation of fibres of the loops in more than one direction of pull on the mass, so that when used as a cleaning and scouring pad it will retain its form and usefulness for the purpose intended until the whole mass is substantially used up and exhausted.
2. A metal wool mass composed of a wound web of substantially parallel filaments of indefinite length, the web consisting of continuous loops 20 with their winding axes extending in an indefinite number of directions and with the web loops

crossing each other and resisting pulls in more than one direction substantially uniformly in the mass to prevent separation of the filaments in order that the mass when used for the purpose intended will retain its shape and usefulness until substantially consumed.

3. A process of producing a metal wool mass composed of a web of substantially parallel filaments of indefinite length which consists in winding the web in loops, changing the axis of one 11 loop gradually with respect to another, thereby causing the minor axis of one loop to be at an angle to the minor axis of another loop, whereby a web loop crosses another web loop for resisting pulls in the mass in more than one direction to 15 prevent separation of the filaments in order that the mass when used for the purpose intended will retain its shape and usefulness until substantially consumed.

GEORGE W. BROOKS. 20
